UNITED STATES PATENT OFFICE.

FRANK H. HUSSEY, OF BEVERLY, MASSACHUSETTS.

DESIGN FOR A SINK-GUARD.

46,529.

Specification for Design.

Patented Oct. 13, 1914.

Application filed July 10, 1914. Serial No. 850,271. Term of patent 14 years.

To all whom it may concern:

Be it known that I, FRANK H. HUSSEY, a citizen of the United States, residing at Beverly, in the county of Essex and State of Massachusetts, have invented a new, original, and ornamental Design for Sink-Guards, of which the following is a specification, reference being had to the accompanying drawing, forming a part thereof.

The figure is a perspective view of a sink guard, showing my new design.

I claim:

The ornamental design for a sink guard, as shown.

FRANK H. HUSSEY.

Witnesses:

CHARLES R. CHRISTOPHER,
N. M. SANBORN.
